UNITED STATES PATENT OFFICE.

WILLIAM H. SILVER AND PHILIP FRIEDLANDER, OF BROOKLYN, NEW YORK,
ASSIGNORS TO SILVER & COMPANY, OF BROOKLYN, NEW YORK, A COR-
PORATION OF NEW YORK.

TOASTER.

SPECIFICATION forming part of Letters Patent No. 712,340, dated October 28, 1902.

Application filed June 7, 1902. Serial No. 110,677. (No model.)

To all whom it may concern:

Be it known that we, WILLIAM H. SILVER and PHILIP FRIEDLANDER, citizens of the United States of America, and residents of 5 Brooklyn, in the State of New York, have invented a new and useful Improvement in Toasters, of which the following is a specification.

This invention relates to toasters designed 10 for use on oil, gas, or gasoline stoves; and it consists in certain novel features of construction hereinafter set forth and claimed.

The leading objects of the invention are to produce a neat article of light weight and 15 without movable parts, to apply the heat directly to the bread through perforations, to equally distribute the heat to the several sides of a pyramidal toaster, and to avoid drying or hardening the bread by confining the heating 20 to the surface of the slice that is to be browned.

Two sheets of drawings accompany this specification as part thereof.

Figure 1 is a side view of the improved 25 toaster. Fig. 2 is a top view. Fig. 3 represents a vertical section on the line A B, Fig. 2. Fig. 4 is a half-plan of the base-piece of the toaster. Fig. 5 is a perspective view of one of its side pieces detached. Fig. 6 is a 30 fragmentary section through one of the corners.

Like letters and numbers refer to like parts in all the figures.

The improved toaster is constructed of thin 35 sheet-iron and wire and comprises a pan-shaped rectangular base-piece 1, four side pieces 2, constructed with corrugations extending from top to bottom and with perforations *a* throughout, an imperforate cap- 40 piece 3, forming the top of the toaster, and four corner-pieces 4 in the form of concavo-con-vex strips embracing the lateral edges of the side pieces 2 and binding them together, as in Fig. 6, and extending through perforations 45 *b* and *c* in the base-piece 1 and cap-piece 3, so that by clenching or upsetting the extremities of the corner-pieces the parts above named are securely united with each other.

The base-piece 1 has upturned stays *d*, Figs. 50 3 and 4, which support the side pieces 2 ex-

ternally at their lower ends, and within the side pieces a circular curb *e* forms an internal support and also conforms the heat-inlet of the toaster to the customary round burners of the stoves for which the toaster is designed. A perforated cone *5*, Fig. 3, having a downturned marginal flange *f* fitted to said curb *e*, insures a proper distribution of the heat within the chamber *g*, Fig. 3, inclosed by the several side pieces 2 and the cap-piece 3.

To render the structure more rigid, a tightening-bell 6, Fig. 3, is inserted within its upper part, and a central tightening-bolt 7 extends upward from the top of this bell through 65 the cap-piece 3.

The other main parts of the toaster are four externally-attached bread-supports 8, each preferably composed of a single wire with its ends *h* rebent at top and inserted through 70 two of the perforations *a* in the side pieces 2. Short pieces 9 of light wire preferably and conveniently fasten the bread-supports 8 to the perforated sides of the toaster below their attaching ends *h*; but such supplemental fastenings may be dispensed with, or the bread-supports may be attached in other known ways, and other like modifications will suggest themselves to those skilled in the art. 75

An upturned marginal flange *i* on the base-piece 1 and a downturned marginal flange *j* on the cap-piece 3 give the article a neat finish and the requisite stiffness and complete its provision with smooth edges. The base-flange *i* facilitates handling the article, and 80 the base-piece is preferably further provided with holes *k*, Fig. 4, to reduce its heat-absorbing area, and thus to keep said flange *i* cool, as well as to further reduce the weight of the article. The cap-flange *j* serves also to 85 assist in fastening the side pieces 2 in place.

In addition to rendering the toaster rigid the tightening-bell 6 serves to regulate the discharge of superheated air through the perforated side pieces 2 by closing the perforations *a* above the lower edges of the bell. 90

By constructing the perforated side pieces 2 with corrugations extending from bottom to top the distribution of the superheated air to all the exposed perforations is materially 95 100

assisted, the sides are rendered stiff and durable, and the joints are protected against injury by the expansion and contraction of the side pieces.

- 5 The corner-pieces 4 not only securely unite the parts, as above described, but by preventing the escape of the superheated air at the edges of the side pieces 2 increase the efficiency of the toaster in operation.
- 10 The side pieces 2 soon become highly heated and the chamber *g* filled with superheated air, which escapes through the perforations *a* against the slices of bread. These are held in close proximity to the perforated sides by 15 the several bread-supports 8, and four slices may conveniently be toasted simultaneously. As the inturned side of the slice is its only part exposed to the heat, drying or hardening the bread in the toasting operation is 20 readily avoided.

Having thus described said improvement, we claim as our invention and desire to patent under this specification—

1. An improved toaster, of pyramidal shape, 25 comprising a sheet-metal base constructed with a central opening, a cap-piece of sheet metal parallel with said base, side pieces of perforated sheet metal surrounding a chamber in communication with said opening at 30 bottom and closed at top by said cap-piece, corner-pieces connecting said base and cap-piece and closing the joints between said side pieces, and means for supporting slices of bread outside of and in close proximity to said 35 side pieces.

2. An improved toaster, of pyramidal shape, comprising a sheet-metal base constructed with a central opening, a cap-piece of sheet metal parallel with said base, side pieces of 40 perforated and corrugated sheet metal surrounding a chamber in communication with said opening at bottom and closed at top by said cap-piece, corner-pieces connecting said base and cap-piece and closing the joints be- 45 tween said side pieces, and means for supporting slices of bread outside of and in close proximity to said side pieces.

3. An improved toaster, of pyramidal shape, comprising a sheet-metal base constructed 50 with a central opening, a cap-piece of sheet metal parallel with said base, side pieces of corrugated sheet metal perforated throughout surrounding a chamber in communication with said opening at bottom and closed at top by 55 said cap-piece, corner-pieces connecting said base and cap-piece and closing the joints between said side pieces, and means for supporting slices of bread outside of and in close proximity to said side pieces.

- 60 4. An improved toaster, of pyramidal shape, comprising a sheet-metal base constructed with a central opening, a cap-piece of sheet metal parallel with said base, side pieces of perforated sheet metal having corrugations 65 extending from bottom to top surrounding a chamber in communication with said opening

at bottom and closed at top by said cap-piece, corner-pieces connecting said base and cap-piece and closing the joints between said side pieces, and means for supporting slices of 70 bread outside of and in close proximity to said side pieces.

5. An improved toaster, of pyramidal shape, comprising a sheet-metal base constructed with a central opening, a cap-piece of sheet 75 metal parallel with said base, side pieces of perforated and corrugated sheet metal surrounding a chamber in communication with said opening at bottom and closed at top by said cap-piece, corner-pieces connecting said base 80 and cap-piece and closing the joints between said side pieces, and bread-supports attached externally to said side pieces.

6. An improved toaster, of pyramidal shape, comprising a sheet-metal base constructed 85 with a central opening, a cap-piece of sheet metal parallel with said base, side pieces of perforated and corrugated sheet metal surrounding a chamber in communication with said opening at bottom and closed at top by said 90 cap-piece, corner-pieces connecting said base and cap-piece and closing the joints between said side pieces, and bread-supports of wire attached externally to said side pieces.

7. An improved toaster comprising a base 95 provided with a circular central opening and curb and with upturned stays, a cap-piece parallel with said base having a downturned marginal flange, side pieces of perforated and corrugated sheet metal surrounding a chamber 100 in communication with said opening at bottom and closed at top by said cap-piece and supported internally at bottom by said curb and externally by said stays and said flange, external corner-pieces connecting said 105 base and cap-piece and closing the joints between said side pieces, a perforated heat-distributing cone embracing said curb within said chamber at bottom, and bread-supports attached externally to said side pieces. 110

8. An improved toaster comprising a base provided with a circular central opening and curb and with upturned stays, a cap parallel with said base-piece having a downturned marginal flange, side pieces of perforated and corrugated sheet metal surrounding a chamber 115 in communication with said opening at bottom and closed at top by said cap-piece and supported internally at bottom by said curb and externally by said stays and said 120 flange, external corner-pieces uniting said base and cap-piece with each other, an internal tightening-bell at top and a tightening-bolt extending upwardly from said bell through said cap, substantially as hereinbefore specified. 125
